UNDERGARMENT

Alfred L. Flesh, Piqua, Ohio, assignor to The
Atlas Underwear Company, Piqua, Ohio, a cor-
poration of Ohio

Application November 22, 1940, Serial No. 366,545

7 Claims. (Cl. 2—234)

This invention relates to nether garments, such as undergarments of the shorts or trunks types, and is concerned more particularly with a novel undergarment for men which is so constructed as to provide a fly opening and also to afford substantial support to the wearer. The new garment may be made in various forms, but, since its novel features afford the greatest advantages when incorporated in legless shorts, a new garment of that type will be illustrated and described for purposes of explanation.

At the present time, men's legless shorts are made in numerous constructions, both with and without fly openings. Garments without such openings are worn only with some obvious inconvenience and, although those garments are usually intended to have a snug fit, they provide little support and the knitted material of which they are ordinarily made is likely to stretch and sag during use. Garments with fly openings as heretofore made likewise do not ordinarily afford substantial support and, in many constructions, the flaps providing the fly opening either gape or sag apart during use, or else are so formed and located that use of the opening is inconvenient because of the great distortion of the parts that is required. In both forms, it is common practise to insert elastic strips in the leg opening hems to cause the hems to fit snugly in the groins of the wearer and the use of such strips adds to the cost of manufacture and may cause discomfort to the wearer.

The present invention is, accordingly, directed to the provision of a novel nether garment which affords the advantages of the prior garments with fly openings, while avoiding their disadvantages and inconveniences. The new garment includes front and back sections connected at their upper ends to a waistband which is preferably of elastic material, although it may be of the draw-string type, if desired. The lower middle part of the front section is formed by a fly insert connected at its lower end to the central portion of the lower end of the back section, and the insert includes a pair of flaps partially overlapping and having free lateral edges so that an opening is formed between the flaps.

The flaps are made of materials having different degrees of vertical extensibility and resilience and the material of the outer flap has the greater resilience and is preferably not extensible horizontally. The flaps may be made of knitted material, with that used for the outer flap including elastic strands so incorporated that the flap has one-way vertical stretch. The outer

flap is formed to cause the insert to afford the desired support and, at the same time, lies snugly in place so that there is no gaping of the fly opening. In addition, the resilience of the outer flap causes the crotch portion of the garment to be drawn in snugly and applies forces to the leg opening hems which prevent them from sagging out of place, even though elastic strips are not inserted in the hems.

10. For a better understanding of the invention, reference may be had to the accompanying drawing, in which

Fig. 1 is a view of one form of the garment in front elevation with a part broken away;

15. Fig. 2 is a vertical sectional view on the line 2—2 of Fig. 1; and

Fig. 3 is an enlarged plan view of material of which the outer flap of the fly section may be made.

20. Referring to the drawing, the new garment is illustrated as including front and back sections 19, 11 which may be made of any suitable material, although, preferably, they are formed of knitted goods and are so cut that the wales of the material run vertically. When thus formed, the sections have horizontal stretch, but are substantially inextensible vertically. The sections are connected together along the side edges 12 of the garment and, for this purpose, the sections may be formed of a single length of tubular fabric or may be secured together by vertical side seams. At their upper ends, the sections are connected to a waistband 13 which is preferably made of an elastic material extensible circumferentially of the garment.

35. The lower middle part of the front section is formed by a fly insert which may be secured to the section by a line of stitching 14 which is preferably of upwardly convex form. The insert includes outer and inner flaps and may be made in various ways, the insert illustrated comprising a pair of side panels 15, 16 and a central flap 17. The upper part of the central flap overlaps the panel 16 and the latter has a free edge 18 which, 40. in the construction shown, is slightly curved and extends at an incline to the vertical. One lateral edge 19 of the central flap is secured to the adjacent edge of the panel 15 and also to an edge 20 of the panel 16. The opposite edge 21 of 45. the central flap is free and, with this arrangement, separation of the overlapping parts of the flap and of panel 16 provides an opening into the interior of the garment.

50. The lower end edge of the back section is provided with portions 22a, 22b which are con-

vergently curved and the central portion 23 of the lower edge of the back section is connected to the lower end of the fly insert. In the construction shown, the central flap 17 extends downwardly past the ends of the panels 15, 16 and the lower end of the flap is connected to the central portion 23 of the lower end of the back section. The lower edges 24 of the front section on either side of the fly insert and the lateral edges 25 of that insert are cut to provide leg openings 26 and the edges of the openings are finished by hem 27.

The central flap 17 and the overlapped portion 28 of panel 16 form outer and inner fly flaps and these flaps are made of materials having different degrees of resilience vertically of the garment. Preferably the outer flap is formed of a knitted material, such as is illustrated in Fig. 3, which has horizontal wales 29 and vertical elastic strands 30. Such material is extensible vertically of the garment and the elastic strand gives it substantial resilience so that it tends to resist stretch. The inner flap 28 may also be made of knitted material and is preferably an integral part of the side panel 16 instead of being a separate piece forming part of the panel. The material of the inner flap may have wales running horizontally or vertically. If the knitted material has horizontal wales, the flap will stretch vertically, but will have little resilience. However, an inner flap made of such material is prevented from sagging by the resilient outer flap. If the inner flap is made of material having vertical wales, it will have substantially no vertical stretch, but the insert as a whole may yield vertically because the outer flap has a portion lying beyond the lower end of the inner flap. Regardless of whether or not the inner flap is made of knitted or woven material, or if made of knitted material whether the wales run horizontally or vertically, the elastic strands 30 incorporated in the outer flap make that flap appreciably more elastic in a vertical direction than the inner flap so that it tends to cling tightly to the body. The side panel 15 is preferably made of the same material as that used in the side panel 16.

With the construction described, the lower end of the fly insert forward of the center of the crotch is formed entirely by the outer flap which is made of the resilient material and is capable of expanding to form a pouch-like supporter. The resilience of the material in the outer flap tends to keep the garment taut in the crotch and in the region immediately upward therefrom along the front and that material tends to keep the free edge 21 of the flap from gaping.

It will be noted that the lateral edges 25 of the lower end of the outer flap form sections of the margins of the leg openings and, since the elastic material in the outer flap tends to contract at all times, the drawing in of these sections exerts a circumferential pull on the remainder of the leg opening hems which insures that those hems will fit snugly around the legs. As a consequence, it is not necessary to employ elastic strips in the leg opening hems of the new garments in order to obtain a snug fit, whereas in prior garments, such strips are common practice.

I claim:

1. A nether garment having leg openings which comprises front and back sections connected along the sides of the garment, a fly section at the lower middle part of the front section including inner and outer overlapping flap mem-

bers having upwardly-extending, oppositely-disposed, free lateral edges, said flap members being disposed so that the space between them and between their upwardly-extending edges affords access to the inside of the lower front portion of the garment, one of said flap members being appreciably more elastic in a direction vertically of the garment than the other flap member, the flap member of greater elasticity forming a part of the leg openings and extending below the other flap member and being connected to the central portion of the lower end of the back section, whereby the contractability of the elastic flap member tends to maintain the leg openings contracted.

2. A nether garment having leg openings which comprises front and back sections connected along the sides of the garment, a fly section at the lower middle part of the front section including inner and outer overlapping flap members having upwardly-extending, oppositely-disposed, free lateral edges, said flap members being disposed so that the space between them and between their upwardly-extending edges affords access to the inside of the lower front portion of the garment, one of said flap members being extensible vertically and having vertically-extending, elastic strands incorporated therein to make it appreciably more elastic in a direction vertically of the garment than the other flap member, the flap member of greater elasticity forming a part of the leg openings and extending below the other flap member and being connected to the central portion of the lower end of the back section, whereby the contractability of the elastic flap member tends to maintain the leg openings contracted.

3. A nether garment having leg openings which comprises front and back sections connected along the sides of the garment, a fly section at the lower middle part of the front section including inner and outer overlapping flap members having upwardly-extending, oppositely-disposed, free lateral edges, said flap members being disposed so that the space between them and between their upwardly-extending edges affords access to the inside of the lower front portion of the garment, the outer flap member being extensible vertically and having vertically-extending, elastic strands incorporated therein to make it more elastic in a direction vertically of the garment than the inner flap member, the outer flap member forming a part of the leg openings and extending below the inner flap member and being connected to the central portion of the lower end of the back section, whereby the contractability of the outer flap member tends to maintain the leg openings contracted.

4. A nether garment having leg openings which comprises front and back sections connected along the sides of the garment, a fly section at the lower middle part of the front section including inner and outer overlapping flap members having upwardly-extending, oppositely-disposed, free lateral edges, said flap members being disposed so that the space between them and between their upwardly-extending edges affords access to the inside of the lower front portion of the garment, both of said flap members being of knitted material, the outer flap member being extensible in a vertical direction to an appreciably greater extent than the inner flap member and having vertically-extending, elastic strands incorporated therein to make it more elastic in a direction vertically of the garment than the inner flap mem-

ber, the outer flap member forming a part of the leg openings and extending below the inner flap member and being connected to the central portion of the lower end of the back section, whereby the contractability of the outer flap member tends to maintain the leg openings contracted.

5. A nether garment having leg openings which comprises front and back sections connected along the sides of the garment, a fly insert forming the lower middle part of the front section and secured thereto, the insert including side panels and a central flap member secured along one side edge to one side panel and overlapping the other side panel, at least a part of the other side edge of the central flap member and the underlying side edge of the overlapped panel being free, said free edges extending upwardly and being oppositely disposed, the central flap member and the underlying side edge being so disposed that the space between them and their upwardly-extending free edges affords access to the inside of the lower front portion of the garment, the central flap member and the overlapped side panel being of materials having different resilience in a direction vertically of the garment, the central flap member being appreciably more extensible and elastic in a direction vertically of the garment than the overlapped side panel, and a connection between the lower end of the insert and a central portion of the lower end of the back section.

6. A nether garment having leg openings which comprises front and back sections connected along the sides of the garment, the lower edge of the back section having portions converging to define a central crotch piece, a fly insert forming the lower middle part of the front section and secured to the forward end of the crotch piece, the fly insert including inner and outer overlapping flap members, said flap members having upwardly-extending, oppositely-disposed, free lateral edges, said flap members being disposed so that the space between them and be-

tween their upwardly-extending, free lateral edges affords access to the inside of the lower front portion of the garment, the outer flap member being extensible vertically to a greater degree than the inner flap member and having vertically-extending, elastic strands incorporated therein to make it more elastic in a direction vertically of the garment than the inner flap member, the lower edges of the front and back sections, the lateral edges of the crotch piece and lateral edges of the fly insert, including lateral edges of the outer flap member, forming leg openings for the garment, the contractability of the outer flap member tending to maintain the leg openings contracted.

7. A nether garment having leg openings which comprises front and back sections connected along the sides of the garment, a fly section at the lower middle part of the front section which includes a pair of flaps having overlapping areas, each of said areas having a free edge and the free edges of the areas being oppositely disposed and spaced apart, the remaining edges of the two flaps defining said areas being connected together, said areas of the flap members being so disposed that the space between them from the free edge of one area to the free edge of the other affords access to the inside of the lower front portion of the garment, one flap member having vertically-extending elastic strands incorporated in it to make it more elastic vertically of the garment than the other flap member, said flap member with the elastic strands extending below the other flap member and having a portion lying between the leg openings and having edges partly defining said openings, the lower end of said portion being connected to the lower end of said back section, whereby the contractability in a vertical direction of said flap member with the elastic strands tends to maintain the leg openings contracted and to cause said flap member to fit the body of the wearer snugly.
